UNITED STATES PATENT OFFICE.

GEORGE E. BURT, OF HARVARD, MASSACHUSETTS.

SILO.

SPECIFICATION forming part of Letters Patent No. 297,564, dated April 29, 1884.

Application filed October 17, 1883. (No model.)

To all whom it may concern:

Be it known that I, GEORGE E. BURT, of Harvard, in the county of Worcester, State of Massachusetts, have invented a new and useful Improvement in Portable Compressing-Silos, of which the following is a specification.

The nature of this invention consists in constructing silos with movable walls, which are held in position with angle-bolts made with

10 screw-threads and nuts so arranged that the side walls and top can move toward each other and diminish the space between the parts, thus compressing the material within the walls to any desirable compactness; also, in arranging

15 a compound lever with toggle-joints all held in position with pivots attached in such a manner to the cover of the silo that a weight applied to the lever will cause the cover to press down on the material in the silo and follow up

20 the pressure with an increasing force as the ensilage settles. The toggle-joints are constructed so that they will be self-acting on the cover and press down on the ensilage with the same operation that compresses the walls of 25 the silo; also, in coating over the planking and joints with an air-excluding material that may be applied in a liquid state and dried, such as varnish, shellac, rosin, or tar, &c.

Heretofore silos were constructed with ma- 30 sonry-work cemented, &c., or with timbers, planking, or double boarding, making them stationary and a part of the building. These were expensive, and only those farmers with a large stock of cattle could afford to have them;

35 but my improved portable silo may be constructed at any place where power and machinery are used and material is cheap, and be taken down and transported to any part of the country. It can be made cheap and of any 40 desirable capacity. Thus a silo may be had at a small cost. I attain these objects by the mechanism illustrated in the accompanying drawings, in which—

Figure 1 is a side view of the silo. Fig. 2 45 is a top view of the silo expanded, ready to fill. Fig. 3 is a top view when the silo is filled and compressed. Fig. 4 is a vertical trans- 50 verse section on the lines 1 and 2. Fig. 5 is a view of detached compressing angle-bolt.

Similar letters refer to similar parts in all the figures.

I construct the silo with upright posts D D,

held together by screw-nuts C C and rod Q, of sufficient length to allow the silo to spread. I construct the sides, platen, and bottom of my 55 silo of plank, jointed and grooved. In the grooves there may be inserted a tongue made of soft wood or some yielding substance, like rubber. The side planks are placed upright and grooved at the bottom end to receive the 60 bottom planks.

I construct the compressing-bands A A A with mitered ends, provided with seats for the compressing angle-bolts B B B B, which are threaded on both arms of the angle, and with screw-nuts C C C, well fitted to these arms, which are of sufficient length to allow the sides of the silo to be expanded to any desirable distance. These bands (two or more) are placed near the top and bottom, 70 as the size of the silo may require, around the outside of the planking, and are held in position with screws N. (Seen in Fig. 1.) In the center of two of the side planking the upright posts D D are placed, provided with 75 pivot-seats M M and locks P P', to lock into the bands A A and the bottom of the silo, and held firmly in place with bolts or screws. The bottom E E' is constructed double, and slides apart or together, as is necessary, and has 80 no opening when the silo is expanded to fill, as is seen in Figs. 2 and 4. The levers F F and their connections are constructed with pivot-seats, and pivoted to post D by pivot G. The connecting-arm H is constructed with 85 pivot-seats, and is pivoted to lever F and toggle-joint by pivots I I. The toggle-joints J J are made of sufficient length to make the desired angle to give the necessary downward motion, and have pivot-seats of sufficient number to admit of adjusting the toggle-joints J J on the posts D D and the platen S, which is constructed with planks having grooves v v in their edges and ends. Into these grooves insert packing. The planks are held together 95 with an upward projection, (center frame,) provided with pivot-seats, and is pivoted to toggle-joints J J by pivots X X. Posts T T T T constructed with three sides to fit the corners of the silo, and of sufficient size to cover the 100 opening in the corners of the silo when it is expanded. Arm O is made to connect toggle-joints J J.

Operation: When the silo is to be filled the

screw-nuts C C are unscrewed and the sides of the silo extended the desirable distance, the bands A A loosened and held in position by the angle-arms B B, the posts T T T T being 5 in position to secure and cover the openings in the corners. The silo, thus enlarged, is filled in the usual manner with the cut ensilage, and, when filled, the platen or cover placed in position, and the arms of the toggle-joint pivoted 10 to the moving platen and post, and the parallel arm O pivoted, as shown in Fig. 1. All the screw-nuts C C C C may be each turned up nearly alike. The force of the screw-nuts will act to draw the sides of the silo together, and as 15 the distance between the posts D D is lessened the toggle-joints will be straightened, and a downward force on the movable platen will cause it to press down on the ensilage and bringing a pressure on all, and thus making a 20 fourfold pressure on the ensilage. In this condition it may be left, to allow it to settle together over night; and by still further turning up the nuts the mass may be more compressed until the plank sides of the silo come in contact 25 with each other at the four corners. The screw-nuts may now be still further turned down and force together all the joints of the planking, thus making an air-tight silo. At this stage, the nuts on the rod Q may be loosened 30 and the connecting-arm O be removed and the platen raised out of the silo-space that has been made by the downward movement of the platen filled with ensilage, and the levers F F and their connections be attached. The platen 35 may now be operated with the levers F F, and as the extra ensilage is pressed down by the action of the compound lever actuating the toggle-joints, and by attaching a weight to the lever F a continued downward force is brought 40 to bear on the ensilage as it settles, and thus get all the advantages of the heavy weight usually employed in pressing the ensilage in

the common-constructed silo, thus saving a large amount of hard labor and making a cheaper and desirable silo; and this silo may be more 45 completely filled, as it does not require a large space for stones or other material for the downward pressure. The posts T T T T cover the openings in the corners when the silo is expanded, and when compressed they slide on 50 the sides and completely fill the angle of the corners fully compressed.

After the ensilage has been compressed, the nuts C C C C are turned up tight on the four sides of the silo, all the joints and corners in the platen and the sides 55 are forced together, and the yielding packing automatically makes an air-tight portable silo.

Having thus described the construction and operation of my invention, what I claim, and desire to secure by Letters Patent, is—

1. A portable compressing silo composed of movable parts, constructed and arranged substantially as described.

2. The mechanism in a silo constructed with laterally-compressing sides, substantially as 60 described.

3. The bands A A, connecting with angle-irons B B, screws and nuts C C, in combination with a silo, substantially as described.

4. The combination of the lever F, the connecting arms H H, the toggle-joints J J, pivots I, I, G, and X, with post D, all arranged 70 in a silo, substantially as described.

5. The combination of the toggle-joints J J J J, the arm O, the posts D D, the platens R 75 and S, and rod Q, all arranged substantially as described.

6. In combination with a silo, the platen R S, constructed with grooves, and yielding packing in its joints, substantially as described.
